UNITED STATES PATENT OFFICE.

ARTHUR L. TRIBBLE, OF MALDEN, MASSACHUSETTS.

MOP.

932,070.

Specification of Letters Patent.

Patented Aug. 24, 1909.

Application filed March 12, 1909. Serial No. 482,896.

To all whom it may concern:

Be it known that I, ARTHUR L. TRIBBLE, of Malden, in the county of Middlesex and State of Massachusetts, have invented certain new and useful Improvements in Mops, of which the following is a specification.

This invention has for its chief object to provide a mop body of suitable flexible absorbent material, with a holder of cheap and durable construction adapted to be firmly engaged with the flexible mop body, and to be detachably coupled to the usual screw threaded mop handle, the construction of the holder being so inexpensive that it can be advantageously put on the market with the mop body, and permanently attached thereto ready for application to a rod or handle, and can be removed from the handle and discarded with the mop body when the latter has been rendered useless by wear.

The invention consists in the improvements which I will now proceed to describe and claim.

Of the accompanying drawings, forming a part of this specification,—Figure 1 represents a side elevation of a mop holder embodying my invention. Fig. 2 represents a side elevation of a portion of a screw threaded mop handle adapted to be engaged with the holder shown in Fig. 1. Fig. 3 represents a side view of a completed mop embodying my invention, including a flexible mop body and the holder shown in Fig. 1, the latter being permanently secured to the mop body. Fig. 4 represents a section on line 4—4 of Fig. 3. Fig. 5 represents a side view of a modification.

The same reference characters indicate the same parts in all the figures.

In carrying out my invention, I provide a mop holder composed of two members of stout wire which are formed from a single length of wire bent back upon itself midway between its ends to form a neck 12 connecting the two members.

Before the completion of the holder, the two members stand side by side parallel with each other. The first step in the operation of converting the wire blank into a mop holder consists in forming the portions of the members which are adjacent to and extend from the neck 12, into a helical coil 13, constituting a socket, the internal surface of which has the equivalent of internal screw threads formed by the inner sides of the con-

volutions of the coil, said convolutions being adapted to engage the threaded end portion 14 of an ordinary mop handle or rod 15. After the coil has been formed, the portions of the wire members not included in the coil, are bent to form two U-shaped arms 16 and 17, which are integral with the convolutions of the coil, and are adapted to be connected to form a continuous frame or band, adapted to surround and to be compressed upon a portion of a flexible mop body.

The ends of the arms 16 and 17 are interlocked or connected by means of an eye 18 on the arm 17 and a hook 19 on the arm 16, prior to the final operation, hereinafter described, of compressing the band upon the mop body, the preferred form of the band prior to said operation being as shown by full lines in Fig. 1.

The mop body employed may be of any suitable construction. I have here shown a mop body 20 composed of parallel ropes of fibrous material, such as loosely twisted cotton yarn, a number of ropes being assembled side by side, and secured together by a band 21 of suitable cloth surrounding the central portion of the group of ropes, and stitched at its edges thereto.

In assembling the mop body and holder, the latter being in the condition represented by full lines in Fig. 1, the ends of the arms 16 and 17 may be disconnected to permit the convenient insertion of the central portion of the mop body in the band formed by said arms, after which the hook and eye are interlocked, and pressure is applied in such manner as to compress the band, and change its form from that indicated in full lines in Fig. 1, to that indicated in Fig. 3, and by dotted lines in Fig. 1. The central part of the mop body is thus securely clamped by the arms 16 and 17, the mop body and holder being inseparably connected. The mop body and holder thus connected may be placed upon the market either with or without the handle 15, so that a purchaser already supplied with a handle, may discard a worn-out mop, including the holder, and apply a new one to the handle.

The construction above described is suitable for flat mops in which the mop body is composed of two side portions depending separately from the holder.

In Fig. 5, I show a modification adapted for so-called "yacht" mops, in which the mop body is composed of a mass of strands assembled in a circular series around a central core or shank. In this modification, the wire blank is bent to form the neck 12 and the two members connected thereby, the members being coiled to form the helical socket 13. The ends of the members which 10 extend from the coil, instead of being formed into the loops 16 and 17, are extended side by side to form a shank or core 22, from which project arms 23 formed by bending portions of the wire members into 15 U-shaped loops, the sides of which are in contact with each other.

The loops project in different directions from the core or shank 22. When the mop body is applied to the shank, the loops 23 20 are embedded in the mop body, the latter being confined upon the shank and loops by external binding cords or ligatures in a well known manner.

24, 24 (Fig. 5) represent the outer ends of 25 the wire members, the inner ends of which are connected by the neck 12. The pressure which compresses the frame or band formed by the U-shaped arms 16 and 17 also compresses the hook 19, so that it is inseparable 30 from the eye 18.

In each embodiment of my invention, a single length of wire is bent to form two members connected by a neck 12 integral with the members, the neck and the adjacent 35 portions of the wire members being coiled to form a screw threaded socket, while other portions of the arms, including the end portions of the length of wire are formed into mop-engaging arms. The neck 12 40 separably connecting the wire members, imparts strength and rigidity to the socket, by preventing the separation of the wire members at the outer end of the coil.

I claim:

1. A mop head composed of a single 45 length of wire bent back upon itself at about its longitudinal center to form two wire members located side by side, and a neck integral with and connecting said members, the portions of said members connected by 50 and adjacent to said neck being helically coiled to form a screw threaded socket, while other portions, including the ends of the wire, are formed to constitute mop-engaging arms integral with the socket. 55

2. A mop head composed of two wire members, portions of which are helically coiled to form a screw threaded socket, while other portions are bent to form flexible U-shaped arms which are integral with the 60 socket, one of said arms having an eye, and the other a compressible hook adapted to engage said eye, the arms when connected by said hook and eye constituting a compressible elongated band adapted to embrace 65 a mop body.

3. As an article of manufacture, a mop comprising a flexible body and a wire holder composed of two wire members, portions of which are helically coiled to form a screw 70 threaded socket, while other portions are bent to form flexible U-shaped arms, one of said arms having an eye, and the other a compressible hook adapted to engage said eye, the arms when connected by said hook 75 and eye constituting a compressible elongated band which surrounds and is compressed upon a portion of the mop body, the hook being also compressed to render it inseparable from the eye. 80

In testimony whereof I have affixed my signature, in presence of two witnesses.

ARTHUR L. TRIBBLE.
